UNITED STATES PATENT OFFICE.

ORLAND D. ORVIS, OF NEW YORK, N. Y., ASSIGNOR, BY MESNE ASSIGNMENTS, TO UNITED FURNACE CORPORATION, OF NEW YORK, N. Y., A CORPORATION OF DELAWARE.

SMOKE-CONSUMING FURNACE.

1,170,989.

Specification of Letters Patent.

Patented Feb. 8, 1916.

Application filed September 16, 1913. Serial No. 790,141.

To all whom it may concern:

Be it known that I, ORLAND D. ORVIS, a citizen of the United States, residing at the city of New York, borough of Manhattan, county and State of New York, have invented a certain new and useful Smoke-Consuming Furnace, of which the following is a specification.

This invention is a furnace wherein steam and air are introduced into the fire chamber for the purpose of burning the smoke and gases, as a result of which increased heat is generated and the objectionable smoke is eliminated. One of the problems in a furnace of this character is the distribution of the steam and air in a manner to thoroughly commingle with the smoke and gases, but in my construction this distribution is effected in a thoroughly satisfactory manner and by 15 one or more nozzles, the inflowing steam and air spreading on diverging lines from said nozzles, so as to substantially cover the whole area of the grate, and in proximity to the bed of fuel.

20 A salient feature of the invention resides in one or more nozzles, although it is preferred to employ a single nozzle, the aggregate area of the outlets in which are equal to the cross sectional area of the pipe or fitting 25 by which the steam and air are supplied to the nozzle, whereby the outflow of the steam and air is not in any manner retarded by frictional contact with the walls of the nozzle or nozzles. Said outlets in the nozzle are in 30 the form of slots and apertures, said slots being positioned to discharge the steam and air on diverging lines, and in proximity to the bed of fuel, so that the steam and air delivered by the nozzle will cover an area 35 within the grate chamber substantially equal to the area of the grate. This results in diffusion of the steam and air uniformly into and through the smoke and gases arising from the burning fuel on the grate, and secures 40 such a thorough combustion of the smoke and gases that no perceptibly colored gases will flow out of the stack, thereby obviating the so-called "smoke nuisance," and securing the further advantage of generating 45 increased heat units for the reason that the carbon in the smoke is consumed and the gases are burned by the addition of air thereto.

In a preferred form, the nozzle is provided with a curved wall, and in this wall

are three slots, two of which are in the same plane and discharge the steam and air at different angles, whereas the third slot is in a different plane from, and is larger than, the other two slots, so as to deliver the air 60 centrally into the furnace chamber. In addition to the slots, the nozzle is formed with apertures, and the aggregate area of these slots and apertures is equal to the cross sectional area of the pipe or fitting to which 65 said nozzle is affixed. The slots and apertures of the nozzle distribute the steam and air in different planes, and so that the streams be directed in crossing lines, the path of flow being close to the bed of fuel, 70 as a result of which the smoke and gases are broken up and the steam and air intimately mixed therewith, whereby the smoke and gases are effectively burned.

The nozzle is positioned, preferably, in 75 the front wall of the furnace chamber, substantially centrally thereof. By using a single nozzle operating to diffuse the steam and air as described, superior results are obtained and the device can be installed easily 80 and economically; in fact, the device is capable of use in all kinds of boiler furnaces, and in furnaces the construction of which is such as to render it difficult, if not prohibitory, to install air and steam feeding 85 appliances of other constructions.

The invention embodies, also, a construction of bridge wall provided with a plurality of arches and rising above the bridge wall so as to substantially embrace the 90 boiler. The flues in the bridge wall tend, in a measure, to retard the outflow of the smoke and gases and to result in a circulation thereof upwardly within the fire chamber and around the boiler, thus securing increased contact of the heat with the boiler, but by injecting the steam and air from the nozzle toward the arches in the bridge wall, no objectionable impedance in the draft through the fire chamber and the flue will 100 follow from the arches retarding the outflow of the gases.

Another feature of the invention is a water circulating pipe positioned within the fire chamber so as to be exposed to the 105 heat thereof for the purpose of securing a circulation of water directly through said chamber, thus exposing the water to the direct action of the heat resulting in a quicker heating of the water and a more rapid cir- 110

culation thereof. It is preferred to employ within the chamber a water pipe the diameter of which exceeds that of the circulating pipes which are connected to the front and rear of the boiler, said water pipe being of greater capacity than the circulating pipes and united thereto by reducing couplings.

Other features of the invention, and the advantages thereof, will appear from the following detailed description.

In the drawings, Figure 1 is a vertical section, partly in elevation, of a furnace equipped with means for feeding steam and air thereto constructed in accordance with this invention. Fig. 2 is a vertical cross section on the line 2—2 of Fig. 1 looking in the direction of the arrow. Fig. 2^a is a vertical section, partly in elevation, illustrating the means for supplying steam and air to the discharging nozzle. Fig. 3 is a horizontal section, partly in plan, on the line 3—3 of Fig. 1. Figs. 4, 5 and 6 are enlarged detail views of a preferred form of distributing nozzle; Fig. 4 being a horizontal section on the line 4—4 of Fig. 6; Fig. 5 being a front elevation of the nozzle, and Fig. 6 being a longitudinal section on the line 6—6 of Fig. 5.

A indicates a boiler, B a fire chamber containing a grate b, C is a bridge wall, all of which are usual in the art. Fuel is supplied to the grate through charging doors b' separated by an intermediate wall b², and air is supplied beneath the grate through the ash-pit door opening b³.

According to this invention the bridge wall C is extended upwardly at C' so as to substantially embrace the boiler, as shown in Figs. 1 and 2, and in this upwardly extending part of the bridge wall are provided openings c, arched as at c', and separated by columns c².

The arched openings c provide for the outflow of gases and other products of combustion from the fire chamber B into the rearwardly extending flue or combustion chamber B', and these openings used in connection with the upwardly extending part C' of the bridge wall secure the upward circulation of some of the smoke and gases upwardly within the fire chamber and into contact with the boiler, thus securing increased steaming capacity.

The steam and air are supplied to the combustion chamber by one or more nozzles D, a preferred form of said nozzle being shown in Figs. 4, 5 and 6. Said nozzle is shown as having a threaded opening d into which is screwed a pipe E, for the purpose of feeding steam and air to the chamber d' of the nozzle. A salient feature of the nozzle is a curved wall e in which is provided a series of slots f g h and openings i i' i². The slots f g are in the same horizontal plane and open 65 through the nozzle at the respective sides of

the vertical central line thereof, so as to discharge the steam and air on diverging lines into the fire chamber B. The other slot h is in a plane below that of the slots f g, and this slot h exceeds the length of either slot f g, said slot h opening through the middle part of the curved wall e so as to discharge the steam and air centrally into the fire chamber, the air flowing out of the slot h intersecting with the streams of steam and air flowing out of the slots f g. The aperture i² is positioned intermediate the slots f g, whereas the other apertures i i' are at the respective ends of slot h, said apertures i i' and slot h being in the same transverse plane.

The aggregate area of the slots f g h and apertures i i' i² is equal substantially to the cross sectional area of pipe E, thus insuring the free outflow of steam and air through the various exits of the distributing nozzle and avoiding any substantial impedance of the outflowing air by frictional contact with the walls of the slots and apertures.

Nozzle D and feed pipe E are embedded within the wall b² which separates the charging openings b', the curved wall e of the nozzle opening through the rear face of wall b² so that the steam and air will be discharged into the fire chamber from a centrally positioned nozzle. The pipe E extends through the front face of wall b², and to this end of the pipe is attached a fitting F, the latter operating to couple together an air inlet pipe G and a steam pipe H. Said steam pipe is connected with the boiler above the water level therein for the purpose of taking steam from the boiler and delivering the same under pressure to a jet nozzle h', the latter being positioned within fitting F and facing toward the pipe E, whereby the steam flowing under pressure from nozzle h' induces the free inflow of air through pipe G into said pipe E, through which pipe E the steam and air flows to nozzle D, by which the steam and air is distributed in a comparatively thin sheet within fire chamber B, substantially over the entire area of the grate b therein, and in close proximity to the bed of fuel.

The fitting F is shown as having a removable plug f' positioned so that an operator can obtain easy access to the steam nozzle h'. The air tube G is open at the lower end across which opening is positioned a screen h², but these details may be modified as desired by a skilled constructor.

I designates a water heating pipe positioned within fire chamber B, preferably at one side thereof. This pipe is provided at its end portions with reducing couplings h l, said couplings operating to connect circulating pipes K L with the respective end portions of the heating pipe I. The cross sectional area of heating pipe I exceeds the cor-

responding area of the corresponding pipes K L so that the heating pipe I will be of greater capacity than the circulating pipes, thus providing for the rapid heating of water within pipe I by the direct action of the heat and gases within chamber B. Pipe K extends rearwardly from heating pipe I, and is adapted to be connected to the rear part of the boiler, whereas the other pipe L extends from the front part of pipe I and is connected with the front part of the boiler, as shown in Fig. 1.

The operation is apparent from the foregoing description taken in connection with the drawings. When the furnace is in use, steam is supplied by pipe H to fitting F, and is blown into pipe E, thus inducing the inflow of air through pipe G, fitting F, and pipe E into nozzle D.

The slots and apertures in the curved wall of the nozzle distribute the air in a thin sheet within the fire chamber, substantially throughout the area of the grate therein, and in close proximity to the bed of fuel, whereby the steam and air tends to break up the smoke and gases and they become intimately mixed with the smoke and gases so as to consume the carbon in the smoke and burn the gases, as a result of which increased heat is generated and the gas issues in an almost imperceptible vapor from the smoke stack of the furnace. The arched openings in the extended part of the bridge wall operate in a measure to increase the free outflow of gases so that there will be a circulation of heat and gases downwardly within the chamber B in front of the extended part C' of the bridge wall, thus bringing the heat into more intimate contact with boiler A, but as steam and air is blown through the nozzle D toward the arched openings in the bridge wall, there will be no obstruction to the outflow of gases from fire chamber B into flue or chamber B'. Water circulates through heating pipe I, being supplied by pipe K and returned to the boiler through pipe L, whereby the water is heated by the direct application of heat within chamber B and a rapid circulation of water through the pipe is secured with a view to increasing the steaming capacity of the boiler.

The parts of my invention are simple and durable in construction, easily installed in ordinary furnaces, and they are susceptible of manufacture and installation economically.

The slots and openings in the distributing nozzle are positioned with a view to securing an important function in the action of the steam and air upon the smoke and gases, to wit: a breaking up of the smoke and gases and a thorough admixture of the steam and air therewith. It will be noted that the slots f g and aperture i² direct

streams of steam and air in a different plane, whereas slot h and apertures i i' direct streams of steam and air in a different plane, but the streams in the different planes from the slots and apertures are delivered on lines 70 which cross or intersect in both horizontal and vertical planes (see Figs. 1 and 3), and, furthermore, the streams of steam and air from the circular holes i i' i² are of a different form from the narrow sheets issuing 75 from slots f g h, as a result of which the steam and air is blown into the smoke and gases on such lines as to break up the cloud of smoke and secure an intimate mixture of the steam and air with the same, thus burning the smoke and gases by a secondary combustion.

The water pipe I is inclined within the grate chamber with a view to facilitating the flow or circulation of water through 85 said pipe. Accordingly, this pipe is not only of greater capacity than the circulating pipes, but it is positioned so that the water flows rapidly through it.

Having thus fully described the invention, 90 what I claim as new, and desire to secure by Letters Patent, is:—

1. In a furnace, the combination with a fire chamber, of a nozzle, and means for supplying steam and air to the nozzle, said 95 nozzle being provided with a plurality of outlets, certain of said outlets being in the form of slots positioned for feeding sheets of steam and air in different planes and in different directions and other of said outlets being in the form of apertures for feeding steam and air on lines which cross with the sheets supplied through said slots.

2. In a furnace, the combination with a fire chamber, of a nozzle provided with a 105 plurality of outlets, certain of said outlets being in the form of slots which operate to diffuse the steam and air in different horizontal planes and in thin sheets, and other outlets being in the form of openings the 110 cross sectional shape of which differs from the first named slots so as to spread the steam and air on lines which intersect with the sheets supplied through the slots, whereby thin sheets of steam and air and streams of steam and air are blown in different planes directly into the smoke and gases for effecting disintegration of the cloud of smoke and gases and the intimate admixture therewith of the inflowing steam and 115 air.

3. In a furnace, the combination with a fire chamber, and a pipe for supplying steam and air, of a distributing nozzle, the delivery face of which is arcuate, said nozzle being provided with a plurality of radially positioned exits the aggregate area of which is equal substantially to the cross sectional area of the pipe, certain of said exits being 125 in the form of slots positioned for direct-

ing the steam and air in thin sheets and in different horizontal planes, and certain other exits being in the form of apertures operating to direct streams of steam and air in directions which cross the sheets of steam and air supplied through the slots.

4. In a furnace, the combination with a fire chamber, and a pipe for supplying steam and air, of a distributing nozzle provided 19 with a series of slots and with apertures the aggregate area of which is equal substantially to the cross sectional area of said pipe, said slots being in different horizontal planes for directing sheets of steam and air

directly into the smoke and gases and said 15 apertures being of a different cross sectional form from the slots, said apertures being positioned relatively to the slots for directing streams of steam and air on lines which cross with the sheets supplied through the 20 slots.

In testimony whereof I have signed my name to this specification in the presence of two subscribing witnesses.

ORLAND D. ORVIS.
